Primary Examiner—Philip S. Hyder*Attorney, Agent, or Firm*—Morton J. Rosenberg; David I. Klein[57] **CLAIM**

The ornamental design for a suitcase bracket, as shown and described.

DESCRIPTION

FIG. 1 is a front-left-top perspective view of a suitcase bracket, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof in a reduced scale wherein the broken lines are shown for illustrative purposes only and form no part of the claimed design.
